UNITED STATES PATENT OFFICE.

CHARLES E. POPE, OF SOUTH HADLEY, MASSACHUSETTS.

MACHINE FOR SOFTENING AND STERILIZING PAPER.

No. 834,488.

Specification of Letters Patent.

Patented Oct. 30, 1906.

Application filed December 26, 1905. Serial No. 293,191.

To all whom it may concern:

Be it known that I, CHARLES E. POPE, a citizen of the United States of America, and a resident of South Hadley, in the county of 5 Hampshire and State of Massachusetts, have invented certain new and useful Improvements in Machines for Softening and Sterilizing Paper, of which the following is a full, clear, and exact description.

This invention relates to a machine or apparatus for the conversion of ordinary, low-grade, smooth, and more or less refractory paper to a paper having a quality, feeling, or texture of very soft character resembling 15 muslin or other fine textile fabric and devoid of the brittle and harsh condition in which the paper is originally found and for also sterilizing and rendering the paper entirely sanitary, the new product having especial desirability and availability as and for toilet 20 purposes to serve as napkins and in some cases to serve as an inexpensive substitute for textile fabric.

The invention consists in the combination 25 or arrangement for coaction of successive means operable on paper substantially as hereinafter fully described, and set forth in the claims.

An object of the invention is to provide an 30 apparatus which is entirely efficient for the production of paper having the quality above indicated.

A further aim of the invention is to so organize the machine as to render it capable of 35 performance of the primary object and with the inclusion of a comparatively few, simple, and inexpensively-constructed parts, the organized machine being operable to produce the paper of the kind required without the 40 employment, so far as softening of the paper is concerned, of any chemical solutions or expensive agencies, although it is the purpose to employ in the bath, through which the paper is carried preparatory to craping it, a disinfectant or sterilizing solution of any simple 45 or approved kind—such, for instance, as a five-per-cent. solution of carbolic acid.

The improved machine is illustrated in the accompanying drawings, in which the figure 50 is a vertical sectional view and partial perspective thereof.

In the drawing, A represents a support for a supply-roll of ordinary smooth paper b, which may be a tissue-paper or a paper considerably heavier than the ordinary tissue-paper.

B represents an upwardly-open tank for containing a quantity of water therein.

C and D represent a pair of peripherally-adjacent feed-rolls, the one, C, of which is partially submerged in the water in the tank, 60 and this roll C has on the endwise-extending journal thereof a driving-pulley d, around which runs a belt f, driven from a pulley g on an overhead counter-shaft h, it being understood that said latter shaft is driven by any 65 suitable means, and the frictional contact between the rolls C and D causes a feed or progression of the paper in the manner shown.

E represents a "doctor" or craping-blade, the same being represented as in an upright 70 position and edgewise bearing against the forward face of the roll D and is a common expedient for the craping of the paper, which by coming around the roll to such blade is obstructed by the latter and diverted from contact on the roll and passes in a crinkled or craped condition into the endless carrier-apron F, which conveys it to the drying action of the drums G and G². These drums are journaled for rotation on horizontal axes 80 and have at their ends spur gear-wheels i i, with which mesh small spur gears or pinions j j, affixed on short shafts or studs k k, and which have also thereon pulleys m m, and one of the stud-shafts k has an additional pulley 85 n, around which runs a belt o, driven by pulley p on the counter-shaft h, and a cross-belt q is in driving engagement around the pulleys m m, so that through these driving connections both drier-drums G and G² are rotated 90 in the same direction.

s s represent carrier aprons or tapes coacting in an ordinary way with the drier-drums for keeping the craped paper in surface contact with the latter, whereby it may 95 be quickly and effectually dried.

In advance of the drier-drums are axially-horizontal compression-rolls H H², one of which has on the extended journal thereof a driving-pulley t, around which runs a belt u, 100 driven by a pulley v on the overhead counter-shaft w, which latter is understood as driven in any suitable manner. These rolls H H² are so set in their bearings that they run in hard peripheral contact one against the 105 other, so that the craped and dried paper being guided and advancing through these rolls becomes decidedly compressed, flattening the surface of the paper and breaking down the fibers thereof. In addition to these 110

rolls serving as compression-rolls either or both thereof may be embossed either with pebbling or with ribs and indentations in any lines or arrangement.

5 J J represent a set of calender-rolls axially horizontally mounted and running in surface contact forward of the compressing-rolls, one of these calender-rolls having on its extended journal a pulley x, which is somewhat smaller than the pulley t on the compressing-roll H, and the driving-belt y runs around the calender-roll pulley and also around the counter-shaft pulley z, which latter is of the same size as the counter-shaft 10 pulley v, so that by this driving connection, in which the pulley x is considerably smaller than the pulley t, the surface-speed of the calender-rolls is faster than the surface speed of the compressing-rolls and whereby a stretching action on the compressed dry craped paper is accomplished between the calender-rolls and the compressing-rolls, the provision of the tension-bar c in proximity to one of the calender-rolls and between it 15 and the compression-rolls being advantageous. The calender-rolls have the function not only of imparting the stretching action to the paper, but also of imparting thereto a final compression.

20 30 The paper after merging from the calender-rolls is wound upon a reel or take-up at K, which may be of any suitable character or construction and involves no invention in this case.

35 The paper introduced in plain smooth condition and subjected to the action of this machine acquires successively three distinct characters or qualities: first, that of ordinary craped paper; secondly, that of a paper in which the craping is not conspicuous and which is more or less pebbled or embossed and very much modified as to the character of the surface inequalities and also very much softer than the paper in the craped or 40 first stage, and the paper has, thirdly, a very soft and muslin-like quality which is so highly desirable in the product and which results from the stretching and final compression in the calender-rolls of the craped 45 paper, which is previously decidedly compressed before reaching the calender-rolls, and the means for compressing or compressing and embossing and breaking down of the fibers of the dried and harsh craped paper before the final stretching thereof is one which 50 is considered of great practical importance in a machine in which this invention is embodied.

60 For the making of paper napkins the action of compressing the crape paper may be accompanied by a simultaneous embossing with pebbling or other ornamental configurations which will plainly show in the finally-finished goods.

I claim—

1. In an apparatus of the character described, the combination with means for supporting and guiding craped paper, of means for compressing the craped paper, and means for stretching the craped and compressed paper. 65 70

2. In an apparatus of the character described, the combination with means for supporting and guiding craped paper, of means for compressing and also embossing the craped paper, and means for stretching the craped and compressed paper. 75

3. In an apparatus of the character described, the combination with means for supporting and guiding craped paper, of means for compressing the craped paper, means for stretching the compressed craped paper, and further and final means for again compressing the stretched compressed craped paper. 80

4. In an apparatus of the character described, the combination with means for supporting and guiding craped paper, of rolls for compressing the craped paper, and means for rotating such rolls, a set of smooth-surfaced calendering-rolls through which the compressed paper is passed, and means for imparting to said calendering-rolls faster surface speed than that of the compressing-rolls whereby the paper between the compression-rolls and said calender-rolls is stretched and whereby the so-stretched paper is finally compressed. 90 95

5. In an apparatus of the character described, the combination with a support for a plain paper-supply, a bath or liquid-tank, means for drawing and guiding the paper through the liquid in the tank, craping means, and a drier to the action of which the paper is carried, of compressing-rolls through which the craped and dried paper is carried, and means in advance of the compressing-rolls for stretching the compressed craped paper. 100 105

6. In an apparatus of the character described, the combination with a support for a plain-paper supply, a liquid-tank, a pair of peripherally-adjacent feed-rolls, one of which is partially submerged in the tank, and a "doctor" or craping-blade coacting with the other of said feed-rolls, means for rotating said feed-rolls, a pair of drier-drums having spur gear-wheels at the ends thereof, shafts having pinions thereon which mesh with the drier-drum spur-gears, and pulleys on said shafts, a crossed belt running around said pulleys, and means for rotating one of said shafts, a carrier-apron located between the craping-blade and drier-drums, endless carrier aprons or tapes coacting with both the drier-drums, a pair of calender-rolls in advance of the compressing-rolls, a driving-shaft having pulleys, a pulley on one of the compressing-rolls, and a smaller pulley on 110 115 120 125

one of the calender-rolls, and belts running around the driving-shaft pulleys and the different-sized pulleys on the compressing-roll, and calender-roll whereby the calender-rolls 5 impart a stretching action to the paper between them and the compressing-rolls.

7. In a machine for making muslin-like paper, the combination of means for supporting and guiding craped paper, comprising a 10 pair of rotating rolls operable to compress the craped paper, and further rolls, in ad-

vance of the compressing-rolls, through which the paper is passed and by which it is drawn at a speed faster than that of its passage through the compressing-rolls, where- 15 by the compressed craped paper is stretched.

Signed by me at Springfield, Massachusetts, in presence of two subscribing witnesses.

CHARLES E. POPE.
